UNITED STATES PATENT OFFICE.

ADDISON G. WATERHOUSE, OF LEONARDO, AND JOHN H. VAN MATER, OF ATLANTIC HIGHLANDS, NEW JERSEY.

ART OF TREATING VEGETABLE AND MINERAL MATTER BY HEAT.

1,105,729.

Specification of Letters Patent.

Patented Aug. 4, 1914.

Application filed August 13, 1913. Serial No. 784,571.

To all whom it may concern:

Be it known that we, ADDISON G. WATERHOUSE, a citizen of the United States, residing at Leonardo, in the county of Monmouth and State of New Jersey, and JOHN H. VAN MATER, a citizen of the United States, residing at Atlantic Highlands, in the county of Monmouth and State of New Jersey, have invented new and useful Improvements in 10 the Art of Treating Vegetable and Mineral Matter by Heat, of which the following is a specification.

Our invention comprises new and useful improvements in the art of baking, firing 15 and annealing brick, pottery, mineral ores and other material; and has for its object the conservation of heat and consequent economy of fuel, and the further object of heating and cooling or annealing the material being treated by a single operation and a continuous process.

Our invention primarily consists of an elevated closed tunnel kiln, insulated to prevent its heat from being lost through radiation or conduction.

It further consists of means for transferring the heat from the material after being raised to its highest temperature to other material before it is raised to its highest or 20 finishing temperature.

The means for carrying out our invention comprise a closed elevated tunnel from which air or gas within the tunnel is sealed from the outer atmospheric air with an external mechanism for carrying different 35 bodies of the material being treated through the tunnel in opposite directions while they continue thermally contiguous to each other, and means for applying heat to the material 40 being treated while approximately mid-way on its course through the tunnel.

The foregoing is set forth in the following specification and pointed out in the claims, the accompanying drawings being a 45 part thereof, in which:

Figure 1, shows a plan of an apparatus embodying our invention; Fig. 2, is an enlarged cross-section of Fig. 1, taken at dotted line Y; Fig. 3, is an enlarged cross-section 50 of Fig. 1, taken at dotted line Y'; Fig. 4, shows a side elevation of a part of a carrying truck.

Fig. 1, shows a plan of an apparatus comprising an elevated tunnel T, T', with a 55 furnace H, through which the tunnel extends

and by which heat can be applied to the material to be treated while it is being carried through the tunnel. Under the tunnel or upon a lower plane are two parallel tramways, one consisting of the rail U, and a series of rollers U', and the other of the rail V, and the series of rollers V'; upon these tram-ways carrier trucks are made to run in opposite directions and carry material to be treated through the tunnel while heat is applied to it while passing through the part of the tunnel formed by the furnace H. In this form the tunnel T, T', is supposed to be of considerable length with an elongated furnace H, placed approximately mid-way to its length and so as to constitute part of the tunnel; after heat is applied to the furnace, if two trucks or two separate trains of trucks are both run under the tunnel and furnace so as to carry the material to be treated through the tunnel and furnace in opposite directions so that such material as it advances toward the furnace will be gradually heated by the hot material moving from the furnace, or so that from first to last the cold material after entering the tunnel toward the furnace will absorb the heat from other material passing from the furnace and thus be preheated and then finally heated in the furnace, after which it in turn will be cooled off by giving up its heat to other material moving in the opposite direction; whereby the heat supplied is conserved and used over and over again by causing the heat supplied to the material to be returned to the furnace by other material and causing all the material to leave the tunnel in about as cold a condition as it was in when it entered, hence there is no heat carried away. X, represents a tram-way turn table or any means by which trucks may be shifted from one track to the other and be returned through the tunnel.

Fig. 2, shows an enlarged cross-sectional elevation of the tunnel T, taken at dotted line Y, of Fig. 1, and consisting of a metal roof P, supported by the frame J; and to this plate P, are secured side plates P', P', and to these are secured floor plates P², P², and hanging plates P³, P³, all of which form a square tunnel T, which is lined with a thick body of fire-proof cement or brick P⁴, which serves as a heat insulator. The floor of this tunnel formed by plates P², P², is provided with a narrow open gap formed between the

hanging plates P^3 , P^4 , which extend down to form a gap deep enough for preventing the heated air or gas within the tunnel T , from comingling with the cold air beneath, owing 5 to the lighter or expanded state of the one and the heavier condition of the other. The side plates P' , P' are also shown extended down to aid in preventing the circulation and comingling of the heated gas in the tunnel with the outer atmospheric air. To completely confine the heated air or gas within the tunnel T , a body of water is used extending the whole length of the tunnel, the surface of which water is represented by the dotted line W , and under which the hanging plates P^3 , P^4 extend, so that this water will completely seal the interior of the tunnel T , from the surrounding air and still leave a gap or under passage through which 15 mechanical communication can be maintained between the carrying trucks beneath the tunnel and their load of material within the same. Beneath the level of the tunnel on what may be the ground floor are shown 20 the two parallel tram-ways, one composed of rail U , and the set of rollers U' , and the other of the rail V , and set of rollers, V' . On these tram-ways are shown trucks representing the two trains of carriers referred 25 to in connection with Fig. 1, and which are adapted for carrying different bodies of the material to be treated through the tunnel in opposite directions at the same time. Each of these carriers consists of a vertical plate 30 1, made to move on their respective set of rollers U' , and V' , which plates 1, 1, have saddles 2, 2, upon which the material to be treated is placed or held so as to only occupy, the space shown within the dashed lines bordering the inner space L , L , of the tunnel T . The plates 1, 1, are held vertical by means of the off-set floors 3, 3, and their grooved wheels 4, 4, which run on their respective rails U , and V ; the plates 5, 5, connected to 40 the off-set floors 3, 3, are for preventing the circulation of air. The tram-ways and lower parts of these trucks are shown under the surface of the water represented by the dotted line W , the effect of which is that 45 the water not only seals the gap leading into the tunnel T , but it also keeps the lower parts of the trucks cool.

Fig. 3, shows an enlarged cross-sectional elevation of the furnace H , taken at the dotted line Y' , of Fig. 1; in which is shown the upper plate P , also the floor plates P^2 , P^2 , and their hanging plates P^3 , P^4 , between which is formed the gap leading from the tunnel T , all of which are supported by the outer walls H' , H' , of the furnace, and between which walls the sealing water W , is confined so that its surface will be above the lower edges of the plates P^3 , P^4 , and seal the gap leading to the tunnel T . Above the 60 floor plates P^2 , P^2 , are placed the combustion

chambers with their grate bars H^2 , H^2 , representing any means by which heat can be applied to the apparatus such as by causing the heat and gas of combustion to impinge directly on the material being treated while such heat and gas is on its way to the chimney H^3 or otherwise. In this Fig. 3, one of the plates 1, with its carrying saddle 2, is shown supported by its tram-way V , V' , as described; while the other plate 1, with its carrying saddle 2, is supported by a float W^2 , adapted for being propelled through the water while carrying the material being treated through the tunnel T ; which shows that the tram-ways can be dispensed with, 75 while the water can be used in their place not only for carrying the material through the tunnel but for sealing its heated air or gas from the outer atmospheric air.

Fig. 4, shows a side elevation of one of the carriers, showing its vertical plate 1, and saddle 2, resting on the rollers V' , and its off-set floor with an upright plate 5, supported by one of its wheels 4, resting on the rail V .

It is obvious that the apparatus shown can be made of any irregular or curved form, instead of straight as shown, without departing from the spirit of our invention; and that the length of both tunnel and furnace 95 can be such as may be required for both heating and cooling the material carried through it, such heat being regulated by the intensity at which it is applied and the speed at which the material is carried, 100 through the furnace, both of which may be controlled automatically or otherwise.

The transfer of heat from one body of the material being treated is effected in part by the direct radiation and conduction of 105 heat between the two bodies owing to their being kept thermally contiguous; and in part by the radiation and conduction of the heat from the material which has passed through the furnace to the walls or body of 110 the tunnel and from such to the cooler material on its way to the furnace. The movement of the carriers through the tunnel whether in the form of trucks or floats can be effected by causing each carrier to pull or 115 push another, from some initial source of propulsion.

What we claim as our invention is:

1. A tunnel kiln for burning brick and other products, consisting of an insulated conduit elevated above its foundation to be isolated therefrom and having an underpassage throughout its length formed between two hanging partitions extending downward from the interior of the elevated 120 conduit into a body of water; with an externally driven mechanism reaching through the water and the passageway into the interior of the conduit for carrying material through the same, and a furnace adapted for heating 125 130

the material while it is being carried through the conduit.

2. A tunnel kiln for burning brick and other products, consisting of an insulating conduit held above its foundation by external isolated supports, and having an under-passage formed between two partitions, extending from the interior of the insulated conduit into a body of water used for sealing the interior of the conduit and that of the under-passage from the surrounding atmosphere; in combination with externally operated means adapted for supporting and carrying two separate bodies of material through the conduit in opposite directions at the same time, while causing them to be brought in thermal communication so that the heat of one will be transferred directly

or indirectly to the other, with means for applying heat to both bodies of such material while being carried through the conduit. 20

3. In a tunnel kiln for burning brick and other products, an insulated conduit elevated above its foundation to be isolated therefrom and having an under-passage throughout its length formed between two hanging partitions suspended from the elevated conduit and extending downward therefrom into a body of water used for sealing the interior of the passage and that of the elevated conduit from the outer atmosphere. 25 30
